United States Patent Office

Des. 224,098

Patented July 4, 1972

224,098

CAMPER

Jimmy W. Ammons, Box 175, Magnum, Okla. 73554

Filed Nov. 13, 1970, Ser. No. 25,964

Term of patent 14 years

Int. Cl. D12—10

U.S. Cl. D14—3

Fig. 3

Fig. 1

Fig. 2

FIG. 1 is a side view of a camper of the present invention in the travelling condition;

FIG. 2 is a front view of the camper of FIG. 1.

FIG. 3 is a rear view of the camper of FIG. 1.

FIG. 4 is a side view of the camper of FIG. 1 in the rigged out camping condition;

FIG. 5 is a front view of the camper of FIG. 1 in the rigged out camping condition;

FIG. 6 is a rear view of the camper of FIG. 1 in the rigged out camping condition.

The side opposite to the one shown in FIGS. 1 and 4 is a mirror image thereof.

I claim:

The ornamental design for a camper, as shown and described.
